UNITED STATES PATENT OFFICE.

ALBERT W. ABBEY AND CHARLES W. DOHM, OF BALTIMORE, MARYLAND, ASSIGNEES
TO THE CONTINENTAL ROOFING AND MANUFACTURING COMPANY, OF BALTIMORE,
MARYLAND, A CORPORATION OF MARYLAND.

DESIGN FOR A SHINGLE STRIP.

Application filed January 15, 1925. Serial No. 12,055. Term of patent 14 years.

To all whom it may concern:

Be it known that we, ALBERT W. ABBEY and CHARLES W. DOHM, citizens of the United States, residing at Baltimore, in the State of Maryland, have invented a new, original, and ornamental Design for a Shingle Strip, of which the following is a specification, reference being had to the accompanying drawing, forming part thereof.

In the drawing:

Fig. 1 represents a plan view of a shingle strip showing our new design.

Fig. 2 represents a portion of a roof covering consisting of shingle strips embodying the design.

We claim:

The ornamental design for a shingle strip, as shown.

In testimony whereof we affix our signatures.

ALBERT W. ABBEY.
CHARLES W. DOHM.
